RIFLE HOLDER

Bill Royce Garlington, 2238 S. Piney Point Road 201,
Houston, Tex. 77042

Filed Feb. 10, 1975, Ser. No. 548,258

Term of patent 14 years

Int. Cl. D3—02

U.S. Cl. D22—13

FIG. 1 is a front view of a rifle holder, showing my new design,

FIG. 2 is a side view of the rifle holder, and

FIG. 3 is a back view of the rifle holder.

I claim:

The ornamental design for a rifle holder, substantially as shown and described.
